UNITED STATES PATENT OFFICE.

HENRY G. ASHTON, OF SOMERVILLE, MASSACHUSETTS.

SAFETY-VALVE.

SPECIFICATION forming part of Letters Patent No. 291,126, dated January 1, 1884.

Application filed September 10, 1880. (No model.) Patented in England September 22, 1880, No. 3,849; in Belgium September 27, 1880, No. 52,656; in Canada September 23, 1880, No. 11,789; in France September 29, 1880, No. 138,867, and in Germany October 3, 1880, No. 13,446.

To all whom it may concern:

Be it known that I, HENRY G. ASHTON, of Somerville, in the county of Middlesex and State of Massachusetts, have invented certain new and useful Improvements in Safety-Valves, of which the following is a specification, reference being had to the accompanying drawings, in which—

Figure 1 is a central longitudinal section, 10 Fig. 2 a top, and Fig. 3 a bottom view, of a valve embodying my invention.

In Letters Patent No. 122,756, dated January 16, 1872, to William Camerer, a safety-valve is described which has in substance the parts lettered A, B, D, G, and a' in my drawings, and consequently these parts are not here fully described, my present invention consisting in the combination of the ring f , or a like projection from the valve G, with a shell, the upper part 20 of which forms a spring-casing, and the lower part of which forms, in connection with ring f , the chamber a^2 , and not in any peculiar construction of the valve.

A is the shell, B the bushing or seat, G the 25 valve, and D its spring. The shell A supports the adjusting-screw of spring D, and also serves, with ring f , as a casing for spring D, and the

enlarged lower part of the shell forms, with the ring f of the valve, the chamber a^2 , so that the steam which escapes past the valve enters this chamber a^2 , and escapes from it through one or more holes, a^4 , into the atmosphere; or a single escape-pipe may be used when the waste steam is to be carried to any desired point. The ring f on valve G prevents all but a small part of the waste steam from passing into that part of shell A above the ring f , this being desirable in all cases, and essential when the steam is not allowed to escape freely from the chamber a^2 of shell A.

I do not claim anything described in the patent above named; but

What I do claim as my invention is—

The combination of shell A, bushing B, and valve G, with the ring f , the upper part of shell A serving, in connection with ring f , to form a casing for the spring D, and the lower part of shell A forming, in connection with ring f , the chamber a^2 , as and for the purpose specified.

HENRY G. ASHTON.
